UNITED STATES PATENT OFFICE.

CARL OSCAR ANDERSON, OF LANCASTER, PENNSYLVANIA, ASSIGNOR TO THE CHAMPION BLOWER & FORGE CO., OF LANCASTER, PENNSYLVANIA, A CORPORATION OF PENNSYLVANIA.

CENTRIFUGAL CREAM-SEPARATOR.

1,168,455.

Specification of Letters Patent. Patented Jan. 18, 1916.

Application filed July 21, 1915. Serial No. 41,140.

To all whom it may concern:

Be it known that I, CARL OSCAR ANDERSON, a citizen of the United States, residing at Lancaster, in the county of Lancaster and State of Pennsylvania, have invented certain new and use Improvements in Centrifugal Cream-Separators; and I hereby declare that the following is a full, clear, and exact description thereof, reference being had to the accompanying drawings, which form part of this specification.

This invention relates to centrifugal cream separators and more particularly to separators of the type in which a series of superposed conical separating disks are employed together with a centrally-disposed feed-tube and distributing device adapted to evenly and uniformly distribute the whole milk as it issues through openings in said tube into the spaces between the separating disks.

The objects of the present invention are to provide a simple, efficient, inexpensive and durable cream separator of the character referred to, adapted to evenly and uniformly distribute the milk between the separating disks of the liner in such manner that substantially the same amount of milk will be passed to and through each of the spaces between the disks and out at the upper end of the bowl at a substantially uniform rate of flow or velocity so that the maximum separating efficiency will be realized in each space.

The invention will first be hereinafter more fully described, with reference to the accompanying drawings, which are to be taken as a part of this specification, and then pointed out in the claims at the end of the description.

In said drawings, Figure 1 represents a vertical sectional elevation of a cream separator embodying my invention; some of the conical separating disks being omitted to more clearly illustrate the interior construction; Fig. 2 is a transverse section taken on the line 2—2 of Fig. 1, Fig. 3 is a perspective view of the sleeve which co-acts with the feed-tube in effecting a uniform distribution of the milk. Fig. 4 is a vertical sectional elevation illustrating a modification of the feed-tube and co-acting distributing sleeve; the cylindro-conical casing or bowl and parts of the liner being

omitted; Fig. 5 is a plan view, partly in transverse section, of the parts shown in Fig. 4; Fig. 6 is a side elevation illustrating in full lines the distributing sleeve shown in Figs. 4 and 5 and one of the conical disks of the liner; the feed-tube being indicated in dotted lines; Fig. 7 is a plan view of the sleeve and conical disk shown in Fig. 6; Fig. 8 is a plan view of the conical disk shown in Figs. 6 and 7 detached; Fig. 9 is a vertical sectional elevation of a modification of the feed-tube and sleeve shown in Figs. 1 to 3; the lower part or base portion of the feed-tube being broken away; Fig. 10 is a transverse section taken on the line 10—10 of Fig. 9, Fig. 11 is a side elevation of the sleeve shown in Figs. 9 and 10 detached from the feed-tube; and Fig. 12 is a transverse section taken on the line 12—12 of Fig. 11.

Referring to said drawings, in which the same reference letters are used to denote corresponding parts in different views, the outer casing or bowl A preferably of cylindro-conical form is supported at its lower end on an outwardly flaring or conical base of a centrally disposed feed-tube B with provision for easily detaching it, to permit the removal or insertion of the liner and co-operating parts, by providing exterior threads on the upper end of the feed-tube for engagement with a nut C screwed thereon and having a depending rim or skirt which surrounds the feed-tube with its lower end resting on the upper end of the neck of the casing; said rim having an interior annular flange which fits closely around the neck of the uppermost separating disk or divider plate D¹, so as to provide an annular groove or channel above the neck of the bowl leading to a cream exit c in said rim through which the cream passes into a suitable receiver. The bowl neck is short, terminating at the base of the depending rim of the nut C, in which, below the cream exit, is or are formed or provided a milk exit or exits c¹. When the parts are assembled as shown and the nut C screwed upon the feed-tube, the latter together with the casing and parts therein will be firmly secured together, and the joint between the bowl and base of the feed-tube may be sealed by a suitable packing ring which fits in an annular groove in said base

within a circumferential flange thereon, as is common in this class of devices. The conical base may be integral with the feed-tube or fitted on an exteriorly threaded 5 lower part thereof, between an annular shoulder and a nut screwed on the tube as shown in Fig. 1, and tinned together, so as to provide in effect a structure in which the tube and base are integral. The lower end 10 of the feed-tube is provided with the usual socket to receive the upper end of a vertical shaft or spindle upon which the bowl is supported as usual in this class of machines.

As shown in Figs. 1 to 3, the feed-tube B, 15 is formed or provided with a series of preferably equidistant, radially extending wings or blades *b*, the outer edges of which are formed with flanges *b*¹ which extend at an angle, preferably at right angles, to the 20 main portion and in the direction of rotation; the wings *b*, being arranged beside a corresponding series of wings or blades *e*, projecting radially from a sleeve E, slidably fitted on the feed-tube, so as to provide a 25 vertically disposed channel between each pair of wings, one on the feed-tube and the other on the sleeve, to receive the milk exuding through suitable slots or apertures in the feed-tube, and when said channel is 30 filled the milk will flow through narrow vertical slits between the outer edges of said wings into the spaces between the separating disks or plates of the liner. The feed-tube is preferably provided with slots or apertures 35 which extend from the bottom of the milk passage therein to a point near the upper end of the distributing sleeve E which fits closely around the feed-tube at the top, and between the wings *b*, and is formed or 40 provided at its lower end with a disk *e*² which is grooved on its underside to fit upon an annular flange on the feed-tube; said disk being slotted as at *e*³ to receive the wings *b* and adapt it to be slid on the feed- 45 tube longitudinally thereof in assembling or disassembling the parts; and in assembled position its lower end rests on the annular shoulder or flange at the apex of the cone-shaped base or at the junction of said base 50 with the feed-tube, whereby the lower ends of the distributing channels are normally closed. The wings of the feed-tube and distributing sleeve preferably extend beyond the cream zone, which lies within the circle 55 described by the margins of the openings through the apices of the conical plates of the liner, which plates are notched, as shown to receive each pair of wings, thereby preventing rotation of said plates independently of the feed-tubes. The vertically disposed channels formed by the radially projecting wings of the feed-tube and distributing sleeve are adapted to cause the milk to travel along the front wall *b*² of the 60 wing *b*, in respect to the direction of rota- 65

tion, so that the milk will be uniformly distributed over the surface of said wall throughout the length of the channel before it reaches the slit between the outer edges of the wings, through which it passes into 70 the spaces between the plates of the liner and thus a uniform and even distribution of the milk is effected in suitable condition for effectually separating the cream, which is caused to pass up the outer sides of the 75 distributing sleeve, in the space between the same and the inner margins or apices of the conical separating disks, and thence through the neck of the divider plate or disk D¹, into the annular channel in the lock nut C 80 and out through the cream exit *c*. As will be seen, the distributing channels are closed at both ends, so that no milk entering the feed-tube can escape, except through the vertically-disposed slits or interstices between the radially extending wings of the feed-tube and distributing sleeve. Any desired number of such wings or blades may be employed, though three have given the best results and only three are shown. Within 85 the bowl A, and around the distributing sleeve are placed a series of frusto-conical disks D each having a cylindrical opening at its apex of such size as to adapt it to fit over the distributing sleeve surrounding the 90 feed-tube and leave an unobstructed space around the sleeve between the distributing channels for the passage of cream ascending to the cream exit. The disks D may be slightly separated and held apart by any 95 well known means such as employed in this class of devices. The uppermost separating disk D¹ has a tubular neck or extension *d* which is slightly larger than and surrounds the feed-tube within the neck of the casing, 100 and fits closely against an annular rib or flange *a*, on the interior of the casing-neck, passage therein as at *a*¹, leading to the milk at its upper end, having a skimmed milk to provide a cream passage therethrough, 105 exit *c*¹, and is also closely fitted within an annular rib or flange *c*², on the interior of the rim of the nut C which cuts off communication between the interior of the nut and the interior of the casing-neck, except 110 through the neck of the divider-plate or disk D¹, within which is fitted a detachable ring *d*¹ having a vertical cream passage *d*² therein. The divider-plate or disk D¹ may have the usual ribs thereon to space it from 115 the circumferential wall of the inclosed casing or bowl and provide a passage for skimmed milk up through the casing-neck. 120

In Figs. 4 and 5, I have shown a feed-tube B¹, having four radially projecting wings and provided with spaced apertures through which the milk is discharged into a space between it and a distributing sleeve E¹ also having radially extending wings which in this instance are straight, so that 125 130

the milk issuing through the apertures in the feed-tube enters a vertically disposed channel of arc-shaped form between the feed-tube and distributing sleeve, and flows 5 out through the space between the wings or flanges of the tube and sleeve into the spaces between the separating disks; the wings or flanges of the feed-tube being longer than the flanges of the distributing sleeve to engage 10 notches in the separating disks and hold the latter in a relatively fixed position and prevent rotation thereof independently of the feed-tube.

In Figs. 6, 7 and 8 I have illustrated a 15 modification of the distributing sleeve, which consists of a tubular body E² having vertical slots therein to receive the wings of the feed-tube and adapt it to be slid upon said tube, and integral radially projecting wings or 20 flanges e⁴ for co-action with the radially projecting wings of the feed-tube on which it is fitted; said wings or flanges e⁴ being formed by cutting the tube and turning the cut part outwardly parallel with the wings 25 of the feed-tube; the latter being indicated in dotted lines in Fig. 6. One of the plates of the liner which may be integral with the distributing sleeve or separate therefrom is shown in side view in Fig. 6, and in plan 30 view in Figs. 7 and 8; the latter showing the plate detached so as to more clearly illustrate its construction.

In Figs. 9 to 12 is shown a modification of the feed-tube and sleeve, which, in effect, 35 is a mere transposition of these parts as shown in Figs. 1 and 3. In this instance the feed-tube B² has integral radial wings without the angular terminal flanges shown in Figs. 1 to 3, while the wings of the sleeve 40 are formed with terminal flanges which are turned toward the adjacent wings of the tube in the same manner and for the same purpose as the flanges on the wings of the tube in the form first described. As will be 45 seen, the distribution of the whole milk is the same in both constructions. The letter G denotes the usual space blocks between the separating disks, and H denotes a series of registering apertures arranged one above 50 another, or in line, so as to form a straight passage vertically through the series of disks parallel with the axis of the bowl, to receive a tool for holding the disks together when they are being washed.

55 Having thus described my invention what I claim and desire to secure by Letters Patent of the United States is:

1. In a centrifugal cream separator, a 60 feed-tube having vertical radially projecting wings or blades, and a sleeve fitted on said tube having vertical radially projecting wings or blades arranged beside but slightly separated from the wings of the tube so as to provide vertically-disposed channels between adjacent wings having vertically dis-

posed slits at the outer edges of the wings through which the milk is discharged; said tube having discharge apertures leading into said channels.

2. In a centrifugal cream separator, a 70 feed-tube having integral radially projecting wings or blades, and a tubular co-acting member slidably fitted on said tube and having integral radially projecting wings or blades arranged beside but slightly separated from the wings of the tube so as to provide vertically-disposed channels between adjacent wings having vertically-disposed slits at the outer edges of the wings through which the milk is discharged; said tube 80 having discharge apertures leading into said channels.

3. In a centrifugal cream separator, a feed-tube having vertical radially projecting wings or blades, and a sleeve slidably fitted 85 on said tube having vertical radially projecting wings or blades arranged beside but slightly separated from the wings of the tube; one set of wings each having a terminal flange turned toward a wing of the other 90 set but slightly separated therefrom to provide a narrow vertically-disposed discharge slit between said flange and the outer edge of an adjacent wing and an enlarged channel between the tube and flange; said tube 95 having discharge apertures leading into said channels.

4. In a centrifugal cream separator, a feeding and distributing device comprising a feed-tube having integral radially-projecting wings or blades and a co-acting member slidably fitted on said tube and having integral radially-projecting wings or blades arranged beside but slightly separated from the wings of the tube so as to provide vertically-disposed channels between adjacent wings having vertically-disposed slits at the outer edges of the wings through which the milk is discharged; said tube having discharge apertures leading into said channels. 100

5. In a centrifugal cream separator, a feed-tube having integral radially-projecting wings or blades extending in a straight line from the axis of the tube to a point beyond the cream zone, and a distributing 110 sleeve slidably fitted on said tube having integral radially-projecting wings arranged beside but slightly separated from the wings of the tube so as to provide vertically-disposed channels between adjacent wings; the wings of the tube having terminal flanges turned toward the wings of the sleeve but slightly separated therefrom, thereby providing enlarged vertically-disposed channels between adjacent wings and slits at the outer edges thereof through which the milk is discharged in a thin sheet.

6. In a centrifugal cream separator, a centrally-disposed feed-tube having vertical radially-projecting wings and discharge 125

apertures beside said wings, a sleeve slidably fitted upon said tube and having vertical radially-projecting wings arranged beside the wings of the tube but slightly separated 5 therefrom to provide vertically-disposed distributing channels with vertical discharge slits between the outer edges of adjacent wings, and superposed separating disks or plates supported on said sleeve and 10 revoluble therewith between which the milk issuing through said slits is received.

7. The combination, in a centrifugal cream separator, of a centrally-disposed feed-tube having integral radially-projecting wings and discharge apertures therein 15 beside said wings, and a co-acting distributing device comprising a sleeve slidably fitted upon said tube and having integral radially-projecting wings arranged beside the wings 20 of the tube but slightly separated therefrom to provide enlarged vertically disposed distributing channels, between adjacent wings and narrow vertical slits between the outer edges of adjacent wings, together with 25 superposed separating disks or plates supported on said sleeve and revoluble therewith spaced to receive therebetween the milk issuing through said slits.

8. A feeding and distributing device for 30 cream separators comprising a centrally-disposed feed tube having discharge ports therein and radial wings having terminal flanges extending at an angle thereto in the direction of rotation of the tube, and a 35 tubular co-acting member having radial wings arranged beside but slightly separated from the wings of the tube, whereby vertically-disposed channels are formed with narrow slits at the outer edges of said 40 wings; said channels being closed at both ends.

9. In a cream separator the combination of a bowl having a tubular neck, a centrally-disposed feed tube having discharge 45 ports therein, and a series of superposed slightly separated conical disks supported on said feed-tube and revoluble therewith; the uppermost disk having a tubular neck

closely fitted within the bowl neck and surrounding but slightly separated from the 50 feed-tube, a nut screwed on said tube having a depending rim with milk and cream outlets therein separated by close contact of the rim with the neck of said uppermost disk, there being an annular space around said 55 neck within the neck of the bowl communicating with said skimmed milk outlet above the upper end of the bowl.

10. In a cream separator, a bowl or casing having a tubular neck, and a flaring 60 base, a centrally-disposed feed-tube protruding through said neck, and having a flaring base on which said bowl is seated, a nut screwed on said feed-tube having a depending rim engaging the upper end of the 65 bowl neck and separated from said tube so as to provide an annular channel therein, and a liner composed of superposed conical disks surrounding said tube; the uppermost disk having a tubular neck which protrudes 70 through the neck of the bowl into the depending rim of the nut tightly fitting the interior wall thereof and the interior of the neck of the casing, but separated from the tube to provide a passage for the ascending 75 cream; the rim of the nut having a cream exit at the top and a milk exit at the bottom, said exits being separated by an annular flange fitting tightly against the neck of said uppermost disk, and a detachable ring in 80 the neck of said uppermost disk closely fitting around the feed tube and having a cream passage for the ascending cream; an annular space being provided within the neck of the bowl in communication with 85 said milk exit and with the space between said uppermost disk and the inner surface of the bowl.

In testimony that I claim the foregoing as my own, I affix my signature in presence 90 of two witnesses.

CARL OSCAR ANDERSON.

Copies of this patent may be obtained for five cents each, by addressing the "Commissioner of Patents,
Washington, D. C."

It is hereby certified that in Letters Patent No. 1,168,455, granted January 18, 1916, upon the application of Carl Oscar Anderson, of Lancaster, Pennsylvania, for an improvement in "Centrifugal Cream-Separators," an error appears in the printed specification requiring correction as follows: Page 2, strike out lines 106-110 and insert the following: *to provide a cream passage therethrough, and fits closely against an annular rib or flange a, on the interior of the casing-neck, at its upper end, having a skimmed milk passage therein as at a', leading to the milk;* and that the said Letters Patent should be read with this correction therein that the same may conform to the record of the case in the Patent Office.

Signed and sealed this 1st day of February, A. D., 1916.

[SEAL.]

J. T. NEWTON,

Acting Commissioner of Patents.
